UNITED STATES PATENT OFFICE

THOMAS GORE, OF NEW YORK, N. Y.

WIRES ROPE.

1,099,644.

Specification of Letters Patent.

Patented June 9, 1914.

Application filed February 11, 1913. Serial No. 747,678.

To all whom it may concern:

Be it known that I, THOMAS GORE, a citizen of the United States, and a resident of the borough of Brooklyn, in the county of 5 Kings, city and State of New York, have invented certain new and useful Improvements in Wire Ropes, of which the following is a specification.

The present invention has more particularly reference to wire strands or ropes, and has for its main object the production of a non-spinning rope and the reduction of 10 wear or chafing of the wires in the several layers of wires composing the strand or between the strands composing the rope.

In wire ropes as at present made there is considerable friction or chafing between the 15 layers of wires when bending and passing over sheaves and drums. Furthermore in order to prevent non-spinning of the strand or rope when it is subjected to stresses, it has been customary in the prior art to twist or lay the several layers of the strand or rope in opposite directions so that the spinning tendency of the two layers will neutralize each other. When this construction of the prior art is employed the rope cannot be spliced, and also since the round wires cross each other at an angle, considerable friction and chafing occurs. Furthermore, in ropes of the prior art it has not been possible to twist the strands of the rope in the same general direction as the direction of twisting of the wires to produce the 25 advantageous "Lang-lay" rope, when it is desired to produce a non-spinning rope.

The present invention consists in means interposed between one or more layers of wires of the strand for preventing untwisting or rotation or spinning of the rope or strand when subjected to stresses. Preferably this is accomplished by interposing flat wires between the layers of round wires, whereby the inner and outer layers of wire 35 will be locked together, as it were, to prevent rotation of the rope and to diminish the chafing action of the round wires.

Other features of the invention will appear as the specification proceeds.

In the accompanying drawing the invention is illustrated in several concrete and preferred forms, but changes of construction may be made without departing from the invention.

In the said drawing: Figure 1 is a view

of a rope embodying the invention, showing also one of the strands of same and the intermediate flat wires. Fig. 2 is a view similar to Fig. 1, showing a modified form. Fig. 3 is a cross-sectional view of a rope made according to my invention. Fig. 4 is a cross-sectional view of one of the strands, which may also constitute a completed rope. Fig. 5 is a cross-sectional view of a modified form of the rope.

Similar characters of reference indicate corresponding parts in the several views.

Considering first Fig. 4, 1 indicates an inner layer of twisted round wires, or wires laid spirally, and 2 is an outer layer of twisted round wires, or spirally laid wires. These wires 1 and 2 are the high tensile strength wires and cross each other at an angle whether the inner and outer layers are laid in the same direction (Fig. 1) or in opposite directions (Fig. 2), and therefore have different thrusts in the same length. Interposed between this inner and outer layer of wires are flat wires 3, preferably of soft Basic steel. These wires 3 may be laid either straight longitudinally (Fig. 2) or spirally (Fig. 1).

The structure shown in Fig. 4 may constitute the complete rope, although it is but a single strand. Or several of these strands may be twisted around the core 4 (Fig. 3), in which case the strands may be twisted in a direction opposite to the twist of the outer layers of wires in each strand as in Fig. 1, or in the same general direction as the twist of the outer layer of wires in each strand, to produce the "Lang lay" shown in Fig. 2.

In Fig. 5 the core 5 is a strand like the one shown in Fig. 4, instead of the fibrous core 4 shown in Fig. 3, and in that case a sheathing 6 of flat wires may, if desired, be interposed between the core 5 and the several strands surrounding the same.

What is claimed, is:

1. A wire strand composed of layers of twisted wires of high tensile strength, and a layer of softer wires interposed between the layers of high tensile strength wires.
2. A wire strand composed of a plurality of layers of wires, said layers having different thrusts in the same length, and a layer of softer metal wires interposed between the first-mentioned layers of wires.
3. A wire strand composed of a plurality of layers of wires, said layers of wires cross-

ing each other at an angle, and a layer of softer metal wires interposed between the first-mentioned layers of wires.

4. A wire rope composed of twisted strands, each strand having a plurality of layers of twisted wires, the twist of the outer layer of wires in each strand and the twist of the strands being in the same general direction, and a layer of softer wire interposed between the several layers of wires in each strand for preventing untwisting rotation when the rope is subjected to stresses.

5. A wire strand composed of a plurality of layers of twisted wires, the wires in the several layers being laid in opposite directions, and softer wires interposed between the several layers of wires for preventing untwisting rotation of the strand when it is subjected to stresses.

20 6. A wire rope composed of a plurality of twisted strands, each strand having a plurality of layers of twisted wires, the wires in the several layers being laid in opposite directions, and a layer of softer wire interposed between the several layers of wires in each strand for preventing untwisting rotation when the rope is subjected to stresses.

7. A wire rope composed of a plurality of twisted strands, each strand having a plurality of layers of twisted wires, the wires in the several layers being laid in opposite directions, the twist of the outer layer of wires

and the twist of the strands being in the same general direction and a layer of softer metal interposed between the several layers 35 of wires in each strand for preventing untwisting rotation when the rope is subjected to stresses.

8. A wire rope composed of a plurality of wire strands, each strand consisting of layers of twisted wires of high tensile strength, and a layer of softer wires interposed between the layers of high tensile strength wires.

9. A wire rope composed of a plurality of 45 wire strands, each strand consisting of a plurality of layers of wires, said layers having different thrusts in the same length, and a layer of softer metal wires interposed between the first-mentioned layers of wires. 50

10. A wire rope composed of a plurality of wire strands, each strand consisting of a plurality of layers of wires, said layers of wires crossing each other at an angle, and a layer of softer metal wires interposed between the first-mentioned layers of wires. 55

Signed at New York city, in the county of New York and State of New York this 6th day of February, A. D. 1913.

THOMAS GORE.
